UNITED STATES PATENT OFFICE.

ALLEN E. OSTRANDER, OF RIDGEWOOD, NEW JERSEY.

RAILWAY-TRUCK.

1,244,767.

Specification of Letters Patent. Patented Oct. 30, 1917.

Application filed July 21, 1913. Serial No. 780,243.

To all whom it may concern:

Be it known that ALLEN E. OSTRANDER, residing at Ridgewood, Bergen county, New Jersey, and being a citizen of the United States, have invented certain new and useful Improvements in Railway-Trucks, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a side elevational view of a complete truck formed in accordance with the present invention.

Fig. 2 is a vertical sectional view, the section being taken on line 2—2 of Fig. 1, looking in the direction indicated by the arrows, and

Fig. 3 is a central vertical longitudinal section through the top arch bar casting, including columns and spring-plank saddle, hereinafter described.

Fig. 4 is a fragmentary view of a modification hereinafter described.

In the conventional form of double arch bar truck frame, with separately formed top and bottom arch bars, it is customary to provide a bottom arch bar with horizontal end portions adapted to rest on journal boxes, and with an intermediate horizontal portion upon which rests the spring-plank, etc.

In consequence of this there are four relatively sharp angles in the bottom arch bar which decrease its efficiency.

One of the objects of the present invention is to provide a bottom arch bar of wrought metal resting at its ends on the journal boxes and of such curvature intermediate the journal boxes as will develop the maximum tensile strength of the bar, due to the elimination of angles therein at its middle portion.

It is well known that wrought metal possesses greater tensile strength than cast metal of equal section, hence the use of wrought metal for the bottom arch bar, which in the truck is a tension member of its side frame.

Cast metal is especially adaptable for use in the top arch bar, due to its superior efficiency in compression, hence the top arch bar is formed of cast metal, and to simplify the construction of the side frames, the columns are cast integral with the top arch bar.

To provide an arcuate seat for the long sweeping curve of the bottom arch bar, the two spaced columns of the truck side frame are united by an integral column tie or spring-plank saddle, and depending from the lower face of the spring-plank saddle is a finger adapted to engage with an orifice in the bottom arch bar and the tie bar.

To reinforce the columns and said saddle, I prefer to cast therein a wrought metal spring-plank suspension yoke, which is relatively U-shaped, as best shown in Fig. 3, and extends within the contiguous portions of the top arch bar.

Another object is to provide castings, where available, which will be of such form that they may be readily handled, and which may be packed for shipment in relatively small space.

Another object is to reduce the number of openings in the bottom arch bar, which are commonly provided with wrought metal arch bars, and to standardize the parts of the side frame for convenience of repairs, such as replacement of parts.

Another object is to reinforce the cast portions of the truck, comprising top arch bar, columns and spring-plank saddle, by means of a wrought metal spring-plank suspension yoke, about which is poured the cast metal in such manner that the said spring-plank suspension yoke is exposed, as shown in Fig. 3, thereby providing a smooth and relatively finished surface, upon which may rest the spring-plank of the truck at the bottom, and against it may be positioned the bolster column guides, commonly used with arch bar trucks.

Referring specifically to the parts, 1 is the top arch bar or compression member which, as will be noted, extends across the tops of adjacent journal boxes 2—2, in which are journaled the axles upon which the wheels are mounted.

Cast integral with the top arch bar are the columns 3—3 and the spring-plank saddle 4 with the depending finger 5, before referred to. The bottom face 6 of the spring-plank saddle is curved in the arc of a circle

corresponding to the curvature of the bottom arch bar or extension member 7 and extending downwardly, and longitudinally at each side of the arcuate face 6 are depending flanges 8, a groove being thus formed in the bottom of said spring-plank saddle, and, hence, the bottom arcuate face 6 is depressed within said saddle. As a result, the bottom arch bar is insured better contact with said bottom arcuate face 6, and the groove also serves to prevent torsional displacement of said bottom arch bar with relation to said spring-plank saddle, the finger 5 being adapted to project through a co-incident orifice in said bottom arch bar for the purpose of positioning the said parts with relation to each other.

To reinforce the columns 3, and to provide a bearing face of greater area, the spring-plank saddle is extended at each side at 9, thereby providing a thickened portion at the base of the columns 3. To reinforce the columns and the spring-plank saddle, a spring-plank suspension yoke 10 of wrought metal is inserted, as best shown in Fig. 3, the cast metal surrounding said yoke and entirely inclosing it, if desired, though I prefer to employ the specific arrangement shown in said Fig. 3, wherein the yoke has hooked ends which are embedded in the top arch bar and extends to the surface, at 11, to provide a flat smooth bearing for the spring-plank 12, upon which rests the usual spring seat 13. Said spring-plank may extend across the truck from one side frame to the other, and its ends may terminate at or near the outer edges of the saddles 4, said ends being shown as being fastened to the saddles on opposite sides of the wrought metal yoke 10. The yoke also extends to the surface at 14—14, recesses or cavities 15 being formed in the columns 3 for the reception of cheek plates or bolster column guides 16, which are removably placed in said recesses 15, and bear against the sides of the bolsters 17, for well understood purposes. Resting upon the spring seats 13 and between said seats and the bolsters, are the usual springs 18.

On account of the limits of the cavities in which the cheek plates or bolster column guides 15 are positioned and the relation of guides 16 and the guide members carried by bolsters 17, said guides 16 cannot be removed until the bolster has been sufficiently and abnormally displaced by deliberate intention.

Casting the metal comprising the top arch bar columns and spring-plank saddle about the spring-plank suspension yoke, as indicated, eliminates the necessity of machining or surface dressing to receive the spring-plank and bolster column guides, which surface dressing is commonly required in cast truck side frames, due to the somewhat

roughened surface of the castings as they leave the mold. As seen in Fig. 1, columns 3 of the side frame are provided near their bottoms on their inner sides with offset portions 3^a so spaced as to position the end of 70 the spring plank 12 and assist in holding said spring plank in proper position.

Cast integral with the columns 3 are the brake beam hanger pins 20, which as shown in Fig. 1, serve as supports for the brake 75 beam hangers 21, with which are connected the brake heads 22 in the usual manner.

The tie bar 23 employed in the present construction is of the conventional type, provided with perforations at its ends for the 80 journal box bolts 24, which journal box bolts extend through the outer ends of the top and bottom arch bars, as indicated in Fig. 3, where a separate journal box is employed, as is customary.

85 The finger 5 coincides with a suitable orifice in said tie bar 23, which orifice is in alignment with the orifice referred to in the bottom arch bar and, as will be noted in Figs. 1 and 2, said finger 5 serves as a 90 means for locking the tie plate and bottom arch bar in position.

To avoid perforating the lower arch bar in its middle portion, it may be formed as shown in Fig. 4, in which 7^a indicates a 95 modified form of lower arch bar on which are formed or secured, preferably by welding, the stop lugs 7^b, which will coact with the shoulders 9 to position the lower arch bar with relation to the spring-plank saddle 100 without the necessity of perforating the said lower arch bar for bolts or the finger 5, before referred to.

I claim:

1. In a truck side frame, a top arch bar 105 and spaced columns cast in one piece, in combination with a single bar of ductile metal extending longitudinally of said columns and about which said columns are cast, said bar spanning the space between 110 said columns.

2. In a truck side frame, a top arch bar, columns and a spring-plank saddle cast in one piece, the saddle having an arcuate bottom portion and an integral depending 115 finger, in combination with an insert of ductile metal extending through and connecting the columns.

3. In a truck side frame, a top arch bar, columns and a spring-plank saddle, all cast 120 in one piece, in combination with a wrought metal insert of relatively U-shape connecting said columns.

4. In a truck side frame, a single cast member comprising a top arch bar and 125 spaced columns, in combination with a wrought metal insert of relatively U-shape in said columns lapping the arch bar and spanning the space between the lower portions of said columns.

5. In a truck side frame, a wrought metal spring-plank suspension-yoke of one piece, and a cast member adapted to support said yoke.
- 5 6. In a truck side frame, a cast metal spring-plank saddle having an arcuate bottom face for the major portion of its length and a wrought metal insert serving as a seat for a spring-plank.
- 10 7. In a truck side frame, a top arch bar, columns provided with opposing cavities and a spring-plank saddle formed as an integer, said saddle having an arcuate bottom face extending beyond said columns adapted 70 to contact with a separately formed bottom arch bar, a wrought insert in said integer exposed by said cavities and removable guides positioned in the latter and adapted to bear against the exposed portions of said insert.
- 15 8. In a truck side frame, a compression member formed with integral columns and spring-plank saddle, said spring-plank having a lower face curved in the arc of a circle, the center of which is above the center of the 80 truck side frame, a spring-plank resting upon said saddle, a bolster resiliently supported thereabove, bolster guides positioned in said columns, and an insert held within said columns and being exposed opposite 85 said guides.
- 20 9. In a truck side frame, a top arch bar formed with integral spaced columns and spring-plank saddle, said spring-plank saddle having a continuously curved lower face 90 longer than the distance between said columns and of a radius greater than the distance between said columns, and a reinforcement integral with and connecting said columns and the outer ends of said spring-plank saddle.
- 25 10. In a truck side frame, the combination comprising an integral cast top arch bar, columns and spring-plank saddle, said saddle being provided with an insert of wrought 100 metal serving as a tie for the columns.
- 30 11. In a truck side frame, the combination comprising an integral cast top arch bar, columns and spring-plank saddle, said saddle being provided with an insert of wrought 105 metal serving as a tie for the columns and as an exposed seat for a spring plank.
- 35 12. In a truck side frame, the combination comprising an integral cast top arch bar, columns and spring plank saddle, said saddle being provided with an insert of wrought 110 metal serving as a tie for the columns, said insert being exposed at a plurality of places.
- 40 13. In a truck side frame, the combination comprising an integral cast top arch bar, 115 columns and spring-plank saddle, said saddle being provided with an insert of wrought metal serving as a tie for the columns, said insert extending through the columns and being anchored in the top arch bar.
- 45 14. In a truck side frame, the combination 120 comprising an integral cast top arch bar, columns and spring-plank saddle, said saddle being provided with an insert of wrought metal serving as a tie for the columns, and said saddle having a bottom face with an arcuate portion spanning the space between said columns.
- 50 15. In a truck side frame, a top arch bar, spaced columns and a spring-plank saddle cast in one piece, said saddle having a bottom face of arcuate form in a radius greater than the distance between said columns, and extending beyond said columns at each end and a bottom arch bar having an intermediate curved portion conforming to the 80 curvature of the lower face of said saddle.
- 55 16. In combination in a truck side frame, a wrought metal spring plank suspension yoke combined with a cast metal top arch bar of a truck by casting.
- 60 17. In combination in a truck, a cast metal top arch bar, bolster columns and a spring seat cast as an integer, said columns having enlarged bases each provided with spaced 90 depending flanges directed toward said top arch bar, and a wrought metal bottom arch bar passing between the flanges at each column and interlocking with the sides of said columns.
- 65 18. In combination in a truck, a top arch 95 bar, columns and a spring seat cast as an integer, a separately formed supplemental metal member having an exposed bearing surface and being interlocked with said integer by being cast therewith, and a wrought metal bottom arch bar adapted to interlock 100 with the sides of said columns.
- 70 19. In combination in a truck, a top arch bar and columns cast as an integer with 105 recesses in said columns for removable column guides and a bottom arch bar having opposed sides defining its width and engaging said columns, said bottom arch bar being interlocked with said columns at the sides thereof and at the column-engaging 110 portions of its width-defining sides.
- 75 20. In combination in a truck, a top arch bar, bolster columns provided at their bases with grooved projections having bracing portions connected with said columns at 115 altitudes higher than the grooved portions of said projections, and a wrought metal tension member provided with portions intermediate its ends adapted to interlock with said grooved projections.
- 80 21. In combination in a truck, a top arch bar, columns having means for guiding a bolster, a support for a spring plank, a tension member connected to said top arch bar, and means depending from said support 120 relatively positioning said support and tension member, upon which depending positioning means said member is incapable of imposing torsional stresses.
- 85 22. In combination in a truck, a side 125

- frame having a removable stress member and being provided with a cast column and a metal member having metal characteristics different from that of said column held in permanent relation to said column by being cast therewith. 5
23. In combination in a truck, a side frame provided with cast bolster columns, a bolster extending between said columns, 10 metal members having characteristics different from that of said columns fixedly retained by said columns by being cast therewith, and metal plates held in place by said bolster and engaging the metal fixedly retained by said columns. 15
24. In combination in a truck, a side frame provided with cast metal columns and provided with a separately formed member permanently secured to said columns during 20 the time said columns are formed, said side frame having parts separable from said columns. 25
25. In combination in a truck, a side frame having a top member and bolster columns all formed in a single casting with a separately formed member permanently interlocked with one of said columns without the aid of extraneous securing devices and having a vertical portion exposed to the 30 bolster opening. 35
26. In combination in a truck, a side frame including a top member and bolster columns of cast metal formed as a single casting and a member extending vertically of said column and permanently interlocked therewith without the aid of separately formed securing means and having an exposed face positioned so as to be opposite a normally located bolster. 40
27. In combination in a truck, a side frame provided with a top arch bar and a column both forming parts of a unitary casting, and a separately formed member permanently secured to said column by the mutual interlocking of integral portions of said column and member, respectively, said member having an exposed bearing surface adapted to face toward a bolster side wall. 45
28. In combination in a truck, a side frame provided with a top member and bolster columns forming integral parts of a single casting and adapted to secure a bolster between said columns, and a separately formed metal member permanently secured to each 50 column by cast portions of the latter and having exposed faces arranged so as to be presented toward opposite sides of a bolster. 55
29. In combination in a truck, a side frame provided with a single casting comprising 60 a top arch bar and opposing bolster columns, a separately formed metal member lying against vertical walls of said columns and
- permanently interlocked with each of said columns by cast portions of the latter, and exposed at each column toward the opposing 65 column. 70
30. In combination in a truck, a side frame comprising a top arch bar and a bolster column both forming a part of a single casting, and a separately formed member ex- 75 posed below said top arch bar interlocked with said column, extending vertically there- of and permanently secured thereto by the mutual interlocking of portions of said member and column. 80
31. In combination in a truck, a side frame comprising a top arch bar and cast bolster columns, a bolster, and a separately formed member anchored in said top arch bar, ex- 85 tends vertically of said columns and hav- 80 ing portions interlocking with portions of said columns, said member being exposed opposite the sides of said bolster. 90
32. In combination in a truck, a side frame comprising a cast top arch bar and a cast bolster column, a separately formed member extending into said top arch bar and column and reinforcing the juncture of the last two mentioned elements, some parts of said side frame being removably united with said 95 column. 100
33. In combination in a truck, a side frame comprising a top arch bar, a bottom arch bar separable therefrom and a cast column, and a wrought metal insert cast in and ex- 95 tends longitudinally of said cast column and adapted to aid in securing the latter to said top bar. 110
34. In combination in a truck, a side frame comprising a top arch bar, a spring plank support and a cast column provided near its lower end with an offset portion adapted to assist in positioning a spring plank, and a wrought metal insert cast in and extending longitudinally of said cast column and 105 adapted to aid in forming a strong connection between said top arch bar and column, said insert being partly exposed. 115
35. In combination in a truck, a side frame comprising a top arch bar, a cast bolster column and a lower member extending longitudinally of the side frame, and a metal insert cast in and extending longitudinally of said column and so connected with said top arch bar and lower side frame member 115 as to make a rigid connection between said top bar, column and lower member, said insert having an exposed portion. 120
